UNITED STATES PATENT OFFICE.

WILLIAM A. DOREY, OF NEWARK, OHIO, ASSIGNOR TO HOLOPHANE GLASS COMPANY,
OF NEW YORK, N. Y., A CORPORATION OF NEW JERSEY.

DESIGN FOR A PRISMATIC REFLECTOR.

56,656.

Specification for Design.

Patented Nov. 23, 1920.

Application filed January 9, 1917. Serial No. 141,486. Term of patent 14 years.

To all whom it may concern:

Be it known that I, WILLIAM A. DOREY, a citizen of the United States, residing at Newark, county of Licking, and State of Ohio, have invented a new, original, and ornamental Design for Prismatic Reflectors, of which the following is a specification, reference being had to the accompanying drawing, forming part thereof.

Figure 1 is a perspective of a reflector

showing my new design. Fig. 2 is a bottom plan view of the same.

I claim—

The ornamental design for a prismatic reflector as shown.

WILLIAM A. DOREY.
